UNITED STATES PATENT OFFICE.

HERMAN F. STINDE, OF STEELEVILLE, ILLINOIS, ASSIGNOR TO MARY E. STINDE, OF SAME PLACE.

FIRE-TONGS.

SPECIFICATION forming part of Letters Patent No. 373,418, dated November 15, 1887.

Application filed March 31, 1887. Serial No. 233,243. (No model.)

To all whom it may concern:

Be it known that I, HERMAN F. STINDE, a citizen of the United States, residing at Steeleville, in the county of Randolph and State of Illinois, have invented a new and Improved Construction of Fire-Tongs; and I do hereby declare the following to be a true and correct description of the same, reference being had to the accompanying drawings, making part 10 of this my specification.

My invention consists of a projection or guide-lever extending from the movable leg above or beyond the hinge into an inclosed socket-chamber which is formed in the handle attached to the fixed leg of fire-tongs, the object being to prevent the passing each other of the grasping ends of the legs and to construct simple, practical, and convenient fire tongs.

The drawings are in six figures.

20 Similar letters of reference indicate like parts.

Figures 1 and 2 are perspective views showing the construction of the fire-tongs, with traced lines showing the location and quadrangular form of a socket-chamber, *b*, in the handle *a*, and also the projection or guide-lever *e*, extending from the leg *d* into the chamber in the handle *a* above the rivet *f*, as well as the play of the guide-lever in the chamber and the 30 span of the tongs. Fig. 3 is a detail view showing the construction of the projection or guide-lever *e* above the rivet *f*, extending from the leg *d*. Fig. 4 is a detail side view showing the handle *a* with the fixed leg *c* and the opening to the socket-chamber *b* for the insertion of the projection or guide-lever *e* when not open below, as in Fig. 2, and by traced lines the narrow side of the chamber *b*. Figs. 5 and 6 are cross-sectional views, Fig. 5 showing the chamber *b* at the upper end in the handle *a*, and Fig. 6 showing the lower end of the same chamber.

To accomplish the foregoing object, (using the well-known methods of working metals,) I construct or cast the handle *a* of fire-tongs 45 tapering from about the middle of its length downward, (ornamenting the handle at pleasure,) with one leg, *c*, attached, and with an inclosed quadrangular chamber, *b*, having two sides parallel with each other and of sufficient 50 distance apart to admit a guide-lever, *e*, and to hold it steady in the direction of the opening and closing of the tongs, as shown by traced lines in Fig. 4, and the other two sides tapering downward to give play in the direction of the 55 opening and closing of the tongs for the upper end of the guide-lever *e*, extending from the movable leg *d* above or beyond the rivet *f*, as shown in Figs. 1 and 2, and I construct the movable leg *d* with a guide-lever, *e*, extending above or beyond the hinge-rivet *f*, so as to form a movable fit between the parallel 60 sides of the socket-chamber *b*, and tapering upward from the rivet *f* to increase the play in the upper and wider end of the chamber *b*, 65 as shown by traced lines in Figs. 1 and 2. I am aware that for a similar purpose others have formed in one side of the handle of tongs a recess closed with a plate, (attached to the handle by a screw and the pivot-bolt,) into 70 which fitted a projection from the movable leg; but this invention I do not claim.

What I claim as new, and desire to secure by Letters Patent, is—

In tongs, the combination of the fixed leg, 75 the handle having the socket-chamber formed within it, the movable leg having the tapering projection or guide-lever, and the rivet-bolt, substantially as and for the purposes described.

HERMAN F. STINDE.
